FIG. 3.

Inventor.

Archibald Montgomery Low.

Attorney. W.H. Parker

Patented Nov. 16, 1926.

UNITED STATES PATENT OFFICE.

ARCHIBALD MONTGOMERY LOW, OF LONDON, ENGLAND, ASSIGNOR TO THE LOW
ENGINEERING COMPANY LIMITED, OF LONDON, ENGLAND.

MIXING APPARATUS.

Application filed January 24, 1925, Serial No. 4,479, and in Great Britain February 1, 1924.

This invention relates to mixing apparatus more particularly of the type described in United States Letters Patent No. 1,475,638 in which there is embodied a stationary casing containing two relatively movable drums or rotors provided with interengaging beaters co-operating without contact, the axes of said drums being so relatively displaced that the inner drum lies within the periphery of the outer drum to one side of its centre.

One feature of the present invention consists in the provision of an additional drum or rotor mounted coaxially with and rotatable with the outer drum, said additional drum having peripheral beaters which interengage without contact with the beaters of the inner axially displaced drum above referred to. The provision of the additional drum or rotor is for the purpose of improving the mixture of the materials under treatment and results in a much more intimate admixture and homogeneous emulsion.

A further feature of the invention is an improved form of beater for any roll or all of the drums in question, these being spaced around the drums at any required intervals, for instance such as will permit one drum to be readily withdrawn axially from another and each comprising a substantially straight forward radial edge which may be slightly curved where it joins the hub of the drum and a back edge comprising a straight part leading by a curved part to the rim and to a straight apex or a back edge continuously and reversibly curved. These forms of beater have the advantage that the substance under treatment after striking the straight radial edge will flow up to the apex, follow around the curved back of the beater and strike the radial edge of the next beater, thus rendering every beater effective instead of the substance flowing tangentially along the straight top as would occur with an ordinary rectangular beater, possibly missing the adjacent beater and not falling over and striking the radial edge of the next beater to the full extent. The form of beater described also facilitates manufacture as it permits of ready casting and may dispense with machining, thus resulting in reduction of cost.

An example of a simple form of hand operated mixing mill embodying the present improvements is illustrated in the accom-

panying drawings in which Fig. 1 is a side elevation with casing removed; Fig. 2 is a vertical cross section and Fig. 3, a plan view with part of the casing broken away.

The outer circular casing *a* may consist of a casting and has a dividing partition wall *a*¹ on one side of which are disposed the drums and on the other side the driving mechanism.

The said drums comprising the following, viz, an outer main drum *b* having interiorly directed spaced beaters *b*¹ and open at one side; at the other side are spokes *b*² formed integrally with a boss *b*³ to receive a driving spindle *b*⁴. On the said spindle is also mounted the additional drum *c* having exterior spaced beaters *c*¹ which engage between the exterior beaters *d*¹ of the axially displaced drum *d* the latter being mounted on a spindle *d*² and the beaters of which in turn engage between the interior beaters *b*¹ of the main drum *b*.

The shape of said beaters is clearly shown in Fig. 1 in the case of the outer drum having the straight forward radial edge *x* and a straight portion *z* leading by a curved part to the rim and to the apex which is straight, and in the case of the inner drums, the said back edge is continuously and reversely curved as at *y*. The forward edges of the beaters may be chamfered at the side or sides as at *x*¹.

The inlet for the materials to be treated comprises a hopper *e* or the like discharging above laterally through the partition wall *a*¹ to the drum compartment and the outlet is shown in the form of a faucet *f* having a controlling cock *f*¹⁰ in the opposite wall *f*¹ of said compartment which wall, when closed, is removably secured to the casing as by means of the clamp *f*² having bent ends *f*³ engaging behind a flange *f*⁴ of the casing and a screw *f*⁵ passing through a threaded hole in the clamp and bearing in a socket *f*⁶ formed on the exterior of the wall. The spindles *b*⁴ and *d*² of the outer and inner drums pass through bushes *b*⁵ and *d*³ in the partition *a*¹ and the spindle *b*⁴ has mounted thereon a gear wheel *g* meshing with a pinion *g*¹ of the spindle *d*². There is also a pinion *g*² on the spindle *b*⁴ which in turn meshes with a gear wheel *g*³ on a counter-spindle *g*⁴ extending from the partition and carrying an operating crank or handle *h* for its rotation. By this means a very

high rotational speed can be given to the drums to produce an intimate mixture of the materials, but obviously, the apparatus may be driven by power with or without 5 any intermediate gearing.

The pinions and gear wheels are secured on their respective spindles by nuts ² screwed into reduced threaded ends of said spindles and by unscrewing said nuts on one hand 10 and removing the wall ¹ on the other hand the drums, gearing and spindles may all be readily removed from the casing for cleaning or other purposes.

What I claim as my invention and desire 15 to secure by Letters Patent of the United States is:—

1. A mixing apparatus comprising a stationary casing, two coaxial rotatable drums one within the other and provided with interior and exterior beaters respectively, the beaters of each drum being spaced longitudinally with respect to the axis of rotation of the drums, and a third drum rotatable relatively to the first mentioned drums 25 and having beaters interengaging without contact with the beaters of said first mentioned drums.

2. A mixing apparatus comprising a stationary casing, two coaxial rotatable drums 30 mounted in said casing one within the other and provided with interior and exterior radially disposed beaters respectively, and a third drum rotatable relatively to the first mentioned drums and having exterior radially disposed beaters cooperating with the beaters of the first mentioned drums, the beaters of each drum being arranged in annular series spaced apart longitudinally of the axis of rotation of the related drum.

40 3. A mixing apparatus comprising a stationary casing, a rotatable drum having interior beaters, a second drum within the first drum coaxial with the latter and having exterior beaters, and a third drum within the first drum having exterior beaters cooperating with the beaters of the first and second drums, the beaters of all the drums being of such relative width and annular spacing that those of the second drum 45 can be withdrawn longitudinally through the beaters of the third drum and the beaters of the latter withdrawn longitudinally through the beaters of the first and second drums.

55 4. A mixing apparatus comprising a stationary casing, two coaxial rotatable drums one within the other and provided with interior and exterior beaters respectively, the beaters of each drum being spaced longitudinally with respect to the axis of rota-

tion of the drums, a third drum rotatable relatively to the first mentioned drums and having beaters interengaging without contact with the beaters of said first mentioned drums, the beaters of the several drums being correspondingly formed with each beater having a straight forward radial edge and a back edge comprising a straight part leading by a curved part to the rim and to the apex which is straight. 65

5. A mixing apparatus comprising a stationary casing, two coaxial rotatable drums one within the other and provided with interior and exterior beaters respectively, the beaters of each drum being spaced longitudinally with respect to the axis of rotation of the drums, a third drum rotatable relatively to the first mentioned drums and having beaters interengaging without contact with the beaters of said first mentioned drums, the beaters of the several drums being correspondingly formed with each beater having a straight forward radial edge and a back edge continuously and reversely curved. 70

6. A mixing apparatus comprising in combination an outer casing for receiving the materials to be mixed, a drum mounted for rotation within said casing with its outer periphery closely adjacent the inner wall of the casing and adapted to carry around the material in the casing, beaters arranged on the interior periphery of said drum, a second drum disposed within the periphery of the outer drum and having exterior beaters interengaging those of the inner drum, and a third drum mounted coaxially with the first drum and having peripheral beaters adapted to engage the peripheral beaters of the second drum. 85

7. A mixing apparatus comprising in combination an outer casing for receiving the materials to be mixed, a drum mounted for rotation within said casing with its outer periphery closely adjacent the inner wall of the casing and adapted to carry around the material in the casing, beaters arranged in the interior periphery of said drum, a second drum disposed within the periphery of the outer drum and having exterior beaters interengaging those of the inner drum, a third drum mounted coaxially with the first drum and having peripheral beaters adapted to engage the peripheral beaters of the second drum, and a gearing device disposed exteriorly of the casing for operating the drums. 100

In witness whereof I have signed this specification.

ARCHIBALD MONTGOMERY LOW.
